(57) **CLAIM**

The ornamental design for a flower light device, as shown and described.

DESCRIPTION

FIG. 1 is a perspective front view of the flower light device. FIG. 2 is a top view of the flower light device in FIG. 1. FIG. 3 is a front side view of the flower light device in FIG. 1.

FIG. 4 is an end view of the flower light device in FIG. 1. FIG. 5 is a bottom view of the flower light device in FIG. 1; and, FIG. 6 is a back side view of the flower light device in FIG. 1.

The broken lines shown on the lamp portion of the drawing define the bounds of the claimed design and form no part thereof; and the broken line showing of a mounting stake is for illustrative purposes only and forms no part thereof.
